APPARATUS FOR TESTING SIGNAL IMPULSE GENERATORS

Kurt Hagenhaus, Berlin-Siemensstadt, and Gerd Tiesler, Berlin-Charlottenburg, Germany, assignors to Siemens & Halske, Aktiengesellschaft, Munich, Germany, a German corporation

Application July 30, 1952, Serial No. 301,646

Claims priority, application Germany August 18, 1951

16 Claims. (Cl. 179—175.2)

This invention is concerned with apparatus for supervising and testing the operation of marker impulse generators in a telephone or other signalling system. The marker impulse generator may be of the type described in the copending application Serial No. 301,647, filed July 30, 1952. The impulses produced by such a generator may be used for switching control purposes, e. g. in a telephone system.

The impulses in a generator of the type indicated above are produced by suitable switching means, e. g., control contacts disposed in distinct first and second groups which are for coordinate operation interconnected by associated circuit means. The control contacts and circuit means and also additional control means coacting therewith must be tested and supervised in order to ascertain and to secure proper operation.

The object of the invention is to provide for such impulse generators testing and supervising apparatus comprising switching devices, e. g., rotary switches, for connecting potentials required for the generation of the impulses from the respective groups of control contacts to testing means so as to ascertain coincidence or simultaneous occurrence of the impulses. One of these switches is adapted to successively connect with the testing means potentials of the first group of control contacts and the other switch is adapted to successively connect with the testing means the potentials of the second group of control contacts which coact in a coordinate manner with the control contacts of the first group.

Details of the invention will be described with reference to the accompanying drawings Figs. 1 and 2 showing an embodiment thereof. The drawings should be placed side by side, with Fig. 2 at the right of Fig. 1 and with the correspondingly referenced line in alignment.

The impulse generator, the operation of which is to be supervised and tested, comprises first switching means or control contacts NP1 . . . NP23 which are in a certain time sequence repeatedly successively actuated by suitable means, e. g. by rotary cam means (not shown) and second switching means or control contacts NPz1 . . . NPz13, which are by similar means successively actuated in a different time sequence. The operation is such that the contacts NP1 . . . NP23 are successively actuated during the time when one of the contacts NPz1 . . . NPz13 is in operated position. Accordingly, contacts NP1 . . . NP23 will be successively actuated during the time when the contact NPz1 is in its actuated position. The contact NPz1 is thereafter restored to normal position, in which it is shown, and contact NPz2 is actuated to alternate operating position. The contacts NP1 . . . NP23 are, during the operating interval of contact NPz2, again successively actuated as before. The successive actuation of the contacts NP1 . . . NP23 is repeated for the duration of operation of each of the successively actuated contacts NPz (only some of these contacts being shown in the drawing) until contact NPz13 is finally actuated, when the contacts NP1 . . . NP23 are again

2

successively actuated for the duration of the actuation of contact NPz13. This completes the operating cycle of the impulse generator.

G11 . . . G1299 indicate rectifiers disposed in the circuits extending between the contacts NP1-NP23 and NPz1-NPz13. The designations P11 . . . PXIII23 indicate terminals at which the impulses produced by the generator appear during the operation thereof and may therefore be termed impulse receiving terminals.

10 In addition to the two groups of control contacts NP1 . . . NP23 and NPz1 . . . NPz13 there are provided contacts NPs (right hand upper section of the drawing) which produce synchronizing impulses, and contacts NPf (lower right hand corner of the drawing) for producing successive switching and stepping impulses. These contacts are also operated by suitable means, e. g. rotary cam means (not shown). The contacts NPs are actuated upon starting the rotation of the cam means which operate the control contacts NP1-NP23, and the contacts NPf are similarly operated incident to the actuation of each of the control contacts NPz1 . . . NPz13.

15 There are also provided among other means, the rectifiers such as indicated G11, G12, G123—G124, G125, G146—G1277, G1278, G1299. The remaining rectifiers, as well as resistances included in the impulse generator circuits, have been omitted to avoid encumbering the drawing. The manner of operation by which the impulses are produced at the terminals P11 . . . PXIII23 is described in detail in the previously mentioned copending application Ser. No. 301,647.

20 The supervising and testing of the operations of the control contacts NP1 . . . NP23 and NPz1 . . . NPz13, in their resting as well as in their actuated positions, is in accordance with the invention accomplished by the 25 apparatus shown in the drawing which includes two rotary switches comprising the stepping magnets DW1 and DW2. The stepping magnet DW1 operates the wipers adw1, bdw1 and cdw1. These switch wipers are advanced in step with the actuation of the impulse generator contacts NP1 . . . NP23. The stepping magnet DW2 operates the wipers adw2, bdw2, cdw2, and ddw2. These latter wipers are advanced in step with the actuation of the contacts NPz1 . . . NPz13. Lamps 30 LP1 . . . LP23 and LP1 . . . LPXIII are provided for signalling specific circuit points where faults are discovered, e. g., the absence of a marker impulse on a certain impulse receiving terminal. Lamps S/L1 . . . S/L4 are provided for coaction with the lamps LP1 . . . LP23 and LP1 . . . LPXIII, to signal the specific nature of 35 faults discovered in the course of the testing. The lamps shown at the right hand lower corner of the drawing, marked LRo1, LRo2, LRo3, are operated to indicate failure of the corresponding discharge tubes Ro3, 40 Ro1, Ro2.

45 50 55 The operation is as follows:

The supervising and testing apparatus is started by actuating the key T1 (upper right hand section of the drawing). Ground is thereby connected to the start conductor an1 for starting the drive of the previously mentioned rotary cam means which operate the various contacts. The contact NPs is thereupon operated and relays B and H1 (winding 1) will be energized from ground on NPs, contact 1e, rectifier, contacts of key T1, windings of H1 and B to -60. Relay B operates its contact 2b to connect itself in a holding circuit over 3a1 to ground at 4z. At contact 49b relay B completes an alternate circuit for maintaining the operation of the drive circuit over the conductor an1 independent of the key T1. Relay H1 closes its contacts 6h1 and 7h1 to connect to the grids G of the tube Ro3 potential which causes the tube to become conductive. Relay P3 ener-

gizes now over its winding I which is disposed in the anode circuit of the tube, the energizing circuit extending over contacts 8p3, 9d2, 10d1, to ground at key T2. Relay P3 actuates its contact 11p3, thereby disconnecting the circuit extending over its winding I and completing a holding circuit over its winding P3II. The tube Ro3 extinguishes. A certain potential has meanwhile been placed on the grids G2 of the tubes Ro1 and Ro2 over a circuit including the wiper adw1 which is in zero position. A corresponding potential has also been placed on the grids G1 of the tubes Ro1 and Ro2, over the wipers bdw2 and adw2 respectively. These tubes, Ro1 and Ro2, now become conductive.

Relay P1 (winding I) in the anode circuit of the tube Ro1 energizes over contacts 12p1, 9d2, 10d1, to ground at key T2, and relay P2 (winding I) in the anode circuit of tube Ro2, energized over contacts 13p2, 9d2, 10d1, to ground at key T2. The relays P1 and P2 operate their respective contacts 14p1 and 15p1 and thus complete holding circuits over their windings P1II and P2II. The cam controlled contact NPf (lower right hand corner of the drawing) is closed at the time of these operations and relay E energizes from ground on NPf, 21b, 20a1, 19p3, 18p2, 17p1, 16e, winding of the relay E to -60. Relay E operates its contact 26e, thereby connecting itself in a holding circuit to ground at closed contact 27b.

The above described switching operations take place if the supervising and testing device is in proper operating condition for carrying out the testing. If it is not in proper operating condition, e. g. due to failure of a tube to operate, thereby preventing actuation of one or more of the relays P1 . . . P3, relay A1 (lower right hand corner of drawing) will become energized over a circuit including a contact such as 24p3, 23p2, and 22p1, and the corresponding signal lamp LRo1, LRo2 or LRo3, key T3, contact 50e, winding of A1 to -60. Signal lamp LPr is at the same time operated in parallel with the relay A1. The latter relay operates its contacts 51a1 and 25a1 to provide a holding circuit for its own winding and to maintain the signal lamp operated, which indicates the failure of a tube. These circuits may subsequently be opened by actuating the key T3.

As already described, relay E is energized if the supervising and testing apparatus is in operating condition. Upon closing its contact 28e, relay E causes energization of relay W (right hand bottom section of drawing) from -60, winding of relay W, 28e, wiper cdw1, in zero position, contact 27b to ground. Relay W closes its contact 29w to produce a stepping impulse for the rotary stepping magnet DW1 (right hand upper section of drawing) from ground at cam operated contact NPs, 31e, 29w, DW1, to -60, so as to cause this magnet to advance its wipers adw1 . . . cdw1. The stepping magnet DW2 for the wipers adw2 . . . ddw2 receives a similar stepping impulse due to the operation of contact 30w of the relay W to step its wipers to position 1. Relay W deenergizes when the wiper cdw1 leaves its zero position and the relays P1 . . . P3 are deenergized by the opening of the contact 10d1 which is actuated by the stepping magnet DW1.

The impulse generator has been started over the start conductor an1, as already described, and therefore is operating. The cam controlled contact NPz1 is accordingly placed in its alternate or working position in which it is maintained for an interval during which the contacts NP1 . . . NP23 are for the first time successively actuated. Responsive to closure of NP1 an impulse is produced which becomes effective on the grids of the tube Ro3 and on the grids G2 of the tubes Ro1 and Ro2 over a circuit including wiper adw1 in position 1. The tube Ro3 is not affected by this impulse. Provided that the cam controlled contact NPz1 is in its working position properly operable, the grid G1 of tube Ro1 will receive a potential over the wiper bdw2 in position 1 to make this tube con-

ductive. The contact NP1 also connects current from -50 to the contact NPz13, over the rectifier G1277, causing an impulse at the grid G1 of tube Ro2 over wiper adw2 in position 1 to make this tube conductive. Relays P1 and P2 in the anode circuits of the tubes Ro1 and Ro2 become energized and place their windings II in holding circuits as described before. The tubes Ro1 and Ro2 are again extinguished by the opening of the contacts 12p1 and 13p2.

10 The apparatus thus ascertains in position 1 of the wipers adw1 . . . cdw1 and adw2 . . . ddw2, whether the cam controlled contacts NP1 and NPz1 are in proper working order and whether the cam controlled contact NPz13 is in proper normal position, thereby also testing the proper conductivity of the rectifier G1277.

The rotary stepping magnet DW1, is energized upon next successive actuation of the cam controlled contact NPs from ground on NPs, 31e, 34p3, 33p2, 32p1, DW1 to -60 and wipers adw1 . . . cdw1 are therefore advanced to position 2. Contact 10d1 is opened upon energization of the rotary stepping magnet DW1, thus deenergizing the relays P1 and P2 by opening the circuits of their holding windings.

25 The cam controlled contact NP2 is thereafter closed and if its operation is proper a potential will be connected to the grids G2 of the tubes Ro1 and Ro2, over wiper adw1 in position 2, while corresponding potentials are connected to the grids G1 of these tubes over the wipers bdw2 and adw2, as before. These tubes become again conductive, causing actuation of the relays P1 and P2 which connect their windings II in holding circuits, thereby disconnecting the tubes, as already described. A test potential is also connected to the cam controlled contact NPz13 (in resting position) over the rectifier G1278.

30 Accordingly, the apparatus tests in position 2 of the wipers whether the cam controlled contacts NP2 and NPz1 are in proper working condition and whether the contact NPz13 is in proper normal position, and further, whether the rectifier G1278 is properly operative.

35 If all these elements are in proper working order, the wipers adw1 . . . cdw1 will be advanced to the next position, so as to ascertain in a similar manner the operating conditions of the contacts NP3, NPz1, NPz13 and corresponding rectifier. These test operations are repeated from position to position of the wipers until the wipers adw1 . . . cdw1 are in position 23 to test the operating conditions of the associated cam controlled contacts NP23, NPz1 and the rectifier G1299. The wipers are then stepped to position 24.

40 Relay R (bottom right hand section of drawing) is in position 24 of the wiper cdw1 energized from -60, winding of R, wiper cdw1 to ground at contact 27b. Relay R closes a circuit for energizing relay H (upper right hand corner of drawing) by actuating its contact 38r, the circuit extending from ground at contact 39b, 38r, winding of H to -60. Relay H actuates its contact 40h, thereby connecting its own winding in a holding circuit independent of contact 38r. Relay H1 is now energized over its winding II in a circuit extending from -60, winding II of H1, 35d1, 36d2, 37i to ground. The rotary stepping magnet DW1 receives an impulse over a circuit from -60, DW1, 41y, 42h1, 43w, 44e, to ground and steps its wipers adw1 . . . cdw1 to position 25. Contact 35d1, operated by the stepping magnet DW1, disconnects the winding II of the relay H1 and this relay deenergizes (winding I of relay H1 has been disconnected previously upon release of the key T1). Contact 42h is opened responsive to deenergization of H1 and the stepping magnet DW1 accordingly deenergizes. The interplay between the stepping magnet DW1 and the relay H1 is repeated until the wipers adw1 . . . cdw1 are again in position zero. Relay R deenergizes when the wiper cdw1 leaves position 25.

45 In the zero position of these wipers relay W is again

operated in a circuit from -60, winding of W, contact 28e, wiper cdw1 to ground on 27b. The rotary magnet DW1 receives another stepping impulse over a circuit from -60, DW1, 29w, 31e, NPs to ground and the wipers adw1 . . . cdw1 are stepped to position 1. The rotary magnet DW2 is now also energized from -60, DW2, 30w, 31e, NPs, to ground, advancing the wipers adw2 . . . ddw2 to position 2.

Over the wipers adw2 in position 2 will now be tested the cam controlled contact NPz1 in its normal position and over wiper bdw2 will be tested the operating condition of the cam controlled contact NPz2 in its actuated position, all during the successive actuation of the cam controlled contacts NP1 . . . NP23. The wipers adw1 . . . cdw1 are, during such testing, successively advanced in step with the successive actuation of the contacts NP1 . . . NP23, as already described. The various rectifiers, which are correspondingly switched-in, are also coincidentally tested, as explained before. The tubes Ro1 and Ro2 operate during this test phase likewise, as already described, receiving the potentials for their grids G1 over the wipers adw2 and bdw2.

After completing this testing phase, the wipers adw1 . . . cdw1 are again advanced from their positions 24 and 25 to the zero position and the wipers adw2 . . . ddw2 are thereafter advanced to position 3 to repeat the test for proper coordinate cooperation of the contacts NP1 . . . NP23, with the next successive contact, such as NPz2, etc. etc. to NPz13.

Upon completion of the testing of the cooperation of the contacts NP1 . . . NP23 with the contact NPz13, the wipers adw2 . . . ddw2 will be in position 13. The wipers adw1 . . . cdw1 are again advanced from their positions 24-25 to zero position, relay R being energized in positions 24-25 of wiper cdw1. The relay W thereafter energizes again over wiper cdw1 to ground on contact 27b causing operation of the rotary magnet DW1 which steps its wipers adw1 . . . cdw1 to position 1.

The rotary magnet DW2 is also energized, responsive to operation of relay W and advance its wipers adw2 . . . ddw2 to position 14. Relay Y (right hand center section of drawing) is energized in position 14 of wiper ddw2 and remains energized through to position 25 thereof in a circuit from -60, winding of Y, wiper ddw2 to ground on contact 27b.

The wipers adw1 . . . cdw1 are in step with the actuation of the cam controlled contacts NP1 . . . NP23 advanced from position 1 to position 24, as already explained. The potential required for the firing of the tubes Ro1 . . . Ro2, which is conducted to the grids G1 of these tubes, is obtained over the wipers adw2 and bdw2 in positions 14 to 25 thereof. Relay R will again energize when the wiper cdw1 reaches position 24, thereby again closing its contact 37r to actuate relay H1 by energizing its winding II. Relay Y being operated and having closed its contact 45y in the circuit of the rotary magnet DW2, this magnet will receive a stepping impulse after closure of contact 42h1 and will advance its wipers adw2 . . . ddw2. Contact 36d2 is opened by the actuation of the magnet DW2, thereby disconnecting the winding II of relay H1. The interplay between the rotary magnet DW2 and relay H1 advances the wipers adw2 . . . ddw2 to zero position. The wiper ddw2 leaves position 25 and thereby causes deenergization of relay Y.

Relay Z (left of relay Y) now operates in a circuit from -60, winding I of Z, wiper ddw2 to ground at 27b. At contact 4z, relay Z disconnects relay B and the latter disconnects H by opening its contact 39b. Relay E continues to hold over its own contact 26e and closes contact 46z to ground at 47w. The rotary magnet DW1 is now in interplay with the relay H1 actuated until its wipers adw1 . . . cdw1 are advanced to zero position. Relay R becomes deenergized and since contact 48h is closed, the winding II of relay Z is energized in opposition to winding I, over wiper cdw1 in zero position, and Z

accordingly deenergizes. Other relays which are at this instant operated, thereupon become deenergized.

The supervisory and testing apparatus has in this manner ascertained the proper working condition of the impulse generator. The testing may be repeated as desired, in accordance with exchange regulations.

The potentials required for the testing as indicated in the drawing are tapped from the exchange battery.

The following faults may be discovered in the course 10 of the testing:

1. *Absence of the marker impulse on one of the terminals PII . . . PXIII23.*—The reason for the failure of a marker impulse to appear at one or the other of the terminals may be due to the failure of one of the cam controlled contacts NP1 . . . NP23. In such a case there will not occur the impulse for the grids G2 of the tubes Ro1 and Ro2 which is in proper operation conducted thereto over the wiper adw1 in the corresponding positions 1-23 thereof. The relays P1 and P2 therefore fail to operate. The relay L (top center of drawing) will now be energized in a circuit from -60, winding of L, rectifier, contacts 53p2, 34p2, 31e, NPs to ground. Relay L operates its contact 541 (shown at the left thereof) to connect its winding in a holding circuit to ground at key T2. One of the signal lamps LP1 . . . LP23, corresponding to the respective faulty contact NP1 . . . NP23, will now be operated over the corresponding position of the wiper adw1, in a circuit extending from -60, affected signal lamp, contacts 67p2, 55p1 or 56p2, 571 to ground at 27b.

30 The operation of one of the signal lamps LP1 . . . LP23 in conjunction with one of the signal lamps LPI . . . LPXIII, designates the affected signal receiving terminal PII . . . PXIII23, on which the marker impulse failed to appear.

40 The signal lamp StL1 is at such same time operated over contacts 70p1, 571, to ground at 27b, as a general signal to indicate that a marker impulse has failed to appear.

A substitute impulse generator may now be put in operation and the faulty generator may be checked and put in order. The key T2 is operated to deenergize the relay L, thereby causing disconnection of the operated signal lamps.

2. *Improper marker impulse at one of the terminals PII . . . PXIII23.*—Such condition may be caused by the failure of one of the cam operated contacts NPz1 . . . NPz13 to reach its full working position. In such a case there will not appear a corresponding impulse (over the wiper bdw2) on the grid G1 of the tube Ro1 and such tube will not fire and thus fail to energize the relay P1. However, the required impulse for the grid G1 of the tube Ro2 will be present by way of the wiper adw2 (over which the normal or resting position of the cam controlled contacts NPz1 . . . NPz13 is tested), so that Ro2 becomes conductive causing energization of relay P2.

65 Relay L now energizes again in a circuit from -60, winding of L, rectifier, contacts 52p1, 33p2, 34p3, 31e to ground at NPs. Relay L completes a holding circuit for its own winding at contact 541. After closure of contact 571, there will be operated one of the signal lamps LPI . . . LPXIII corresponding to the position of the wiper adw2, i. e. corresponding to the cam controlled contact NPz1 . . . NPz13 which failed to operate. Contact 67p2 is open and the signal lamps LP1 . . . LP23 therefore remain at rest.

70 The resulting signal (one of the lamps LPI . . . LPXIII operated) designates the group of marker signal receiving terminals affected by the failure of the corresponding cam controlled contact NPz1 . . . NPz13.

The signal lamp *StL1* is operated as described before under the subheading "1."

3. *Short circuit in one of the rectifiers G11 . . . G1299.*—If one of the rectifiers is short circuited, there will be, during the actuation of one of the associated cam controlled contacts *NPz1 . . . NPz13*, a steady potential on the impulse receiving terminal associated with the faulty rectifier. In the various operating positions of the wiper *adw1* a potential will be connected to the grids *G* of the tube *Ro3* causing this tube to become conductive 10 to energize the relay *P3*. A potential is at such time also conducted to the grids *G1* and *G2* of the tubes *Ro1* and *Ro2*, so that these tubes also become conductive to energize relays *P1* and *P2*. Relays *P1*, *P2*, *P3* being energized, the relay *L* will be energized from *-60*, winding *L*, rectifier, contacts *60p3*, *31e* to ground at *NP5*. One of the signal lamps *LPI . . . LPXIII*, which corresponds to the faulty circuit, will now be operated over a circuit including the wiper *cdw2* and contacts *59p3*, *69p1*, *63p2*. In addition the corresponding one of the signal lamps *LP1 . . . LP23* is operated in a circuit including the wiper *bdw1* and contacts *68p3*, *64p3*, *571*, to ground at *27b*. The operation of the two lamps indicates the particular circuit (impulse receiving terminal) containing the faulty rectifier. Signal lamp *StL2* is in this case also operated over a circuit including contacts *71p3*, *571*, to ground at *27b*, to indicate as a general signal that a rectifier is short circuited. 20

4. *One of the rectifiers G11 . . . G1299 is interrupted.*—The proper potentials will in such a case be conducted to the grids *G2* of the tubes *Ro1* and *Ro2* but only *Ro1* will become conductive because the proper firing potential for the grid *G1* will be conducted only to this tube by way of wiper *bdw2*. Accordingly only relay *P1* will be energized. The relay *L* will energize as before. One of the signal lamps *LPI . . . LPXIII*, which corresponds to the circuit containing the faulty rectifier, will be operated over wiper *ddw2* after closure of contact *65p1*, and the corresponding one of the signal lamps *LP1 . . . LP23* will be operated over contacts *67p2* and wiper *bdw1*. 25

The particular lamps which are operated in this manner signal the circuit in which there is an interrupted rectifier. Lamp *StL3* is in this case operated over contact *73p1* to signal the corresponding "rectifier interrupted" condition. 30

In case there are additional cam controlled contacts provided which are e. g. successively actuated prior to the operation of the contacts *NP1 . . . Np23*, to produce impulses for desired switching purposes, such additional contacts may also be tested and supervised. For example, four such additional contacts that may be provided may be connected to the contacts *14—17* of the bank controlled by wiper *bdw2*, so as to cause firing of the tube *Ro1*, if these contacts are in proper worker order. An auxiliary relay may in this case be connected with the bank contacts *14—17* to take care of the switching operations which control the stepping of the wipers *adw2 . . . ddw2*. Additional signal lamps may for such cases be provided which may be connected for operation over the wiper *cdw2* to signal faults of the additional contacts. 35

Several contacts *NPz1* and *NPz2* are provided for load distributing reasons, serving switching control purposes for other exchange equipment cooperating with the impulse generator and subdivided into groups indicated at *G1* and *GII* (right hand upper section of drawing). 40

Between these contacts is disposed the relay *U*. This relay becomes, for the purpose of signalling, energized over one of the contacts responsive to failure of the other contacts to switch-in the signal lamp *StL4* over the contact *66u*. The relay *U* also closes its contact *75u* (upper right hand corner of drawing) to connect its winding *II* in a holding circuit. 45

It may be mentioned in conclusion that electronic stepping means may be substituted for the stepping switches

shown. Electronic switching means may also be substituted for the contact means *NP1 . . . NP23*, as is described in the previously mentioned copending application, Serial No. 301,647. 5

We claim:

1. Apparatus for testing the operation of signal impulse generators having a plurality of a first type switching means and an individual conductor extending from each of said first type switching means and having a plurality of groups of control conductors each group having a plurality of control conductors one for each of said individual conductors and connected with such first conductor and having an impulse receiving terminal connected with each control conductor and having a plurality of a second type switching means one for each group of said control conductors and having means for successively actuating said second type switching means to connect a potential to the associated group of control conductors and means for successively actuating said first type switching means to connect a potential successively to said individual conductors and therewith to said control conductors to produce impulses at said impulse receiving terminals of the group of control conductors associated with an actuated second type switching means, whereby impulses are successively produced at the impulse receiving terminals of the successive groups of control conductors; said apparatus comprising testing means, a first device for successively connecting to said testing means the potentials successively appearing on said individual conductors by the successive actuation of said first type switching means, and a second device for successively connecting to said testing means the potentials respectively connected by said second type switching means to the groups of control conductors respectively associated with said second type switching means, and means in said testing means for ascertaining the simultaneous occurrence of said potentials connected thereto. 20

2. Apparatus for testing the operation of an impulse generator having a plurality of groups of impulse receiving terminals each group comprising several terminals and having a plurality of first type switching means for successively connecting potentials to said terminals in each group and having second type switching means for successively connecting a potential to all said terminals in each group, the coincidence of said potentials on any of said terminals producing a signal impulse thereon; said apparatus comprising testing means, a first device for successively connecting to said testing means the potentials successively connected to said terminals by said first type switching means, a second device for successively connecting to said testing means the potentials successively connected to said groups of terminals by said second type switching means, supervising means in said testing means for testing for the coincidence of said potentials, means governed by said supervising means responsive to establishing coincidence of said potentials connected by said first and second type switching means for controlling the continuous operation of said first and second device, signalling means respectively individual to said first and said second type switching means, and circuit means controlled by said supervising means responsive to failure to establish coincidence due to failure of the respective switching means for operating the signal means corresponding thereto. 50

3. The apparatus defined in claim 2, wherein said testing means comprises a plurality of electron tubes, signal means respectively individual to said tubes, and circuit means responsive to failure of either of said tubes for operating the corresponding signal means. 55

4. The apparatus defined in claim 2, comprising a rectifier associated with each of said impulse receiving terminals, signal means common to a plurality of rectifiers, and circuit means controlled by said supervising means for actuating said last named signal means jointly with the signal means corresponding to the switching

means which caused the failure to establish coincidence.

5. The apparatus defined in claim 2, comprising a pair of stepping switches respectively constituting said first and said second device, and means controlled by said stepping switches for governing the operation of 5 said signal means.

6. The apparatus defined in claim 2, wherein said testing means comprises a plurality of electron tubes, circuit means controlled by said device for connecting said potentials to said tubes, relay means respectively coacting with each of said tubes, and circuit means controlled by 10 said relay means for governing the operation of said first and said second device.

7. The apparatus defined in claim 6, comprising signal means respectively individual to said tubes, and circuit 15 means controlled by said relay means responsive to failure of either of said tubes for operating the corresponding signal means.

8. The apparatus defined in claim 5, comprising additional common signal means, and circuit means for 20 operating said additional common signal means coincident with the operation of said individual signal means.

9. Apparatus as defined in claim 1, wherein said first type switching means are successively actuated during the time of operative actuation of each of said second 25 type switching means.

10. Apparatus as defined in claim 1, wherein stepping switches constitute said first and second device, each of said switches having bank contacts, said first type switching means being connected to bank contacts of one of said switches, and said second type switching means being connected to bank contacts of the other switch.

11. Apparatus as defined in claim 1, wherein stepping switches constitute said first and said second device, each of said switches having band contacts, said first type switching means being connected to bank contacts of one of said switches and said second type switching means being connected to bank contacts of the other switch, and means for successively stepping said other switch for successively connecting said second type switching means to said testing means to test the operatively effective actuated position and also the normal position of said second type switching means.

12. Apparatus as defined in claim 11, wherein said other 45

switch comprises two wipers and bank contacts associated therewith, the actuated position of said second type switching means being tested by said testing means over one of said wipers and the normal position of such switching means being tested by said testing means over the other wiper conjointly with the testing of the actuation of the next successive first type switching means.

13. The apparatus defined in claim 1, comprising stepping switches constituting said first and said second device.

14. The apparatus defined in claim 1, wherein a first stepping switch constitutes said first device and a second stepping switch constitutes said second device, and means for advancing said second stepping switch by one step after each operating cycle of said first stepping switch during which such first switch is successively advanced a plurality of steps.

15. The apparatus defined in claim 1, wherein a first stepping switch constitutes said first device and a second stepping switch constitutes said second device, means for advancing said second stepping switch by one step after each operating cycle of said first stepping switch during which such first switch is successively advanced a plurality of steps, and control contact means for affecting the advance of said stepping switches.

16. The apparatus defined in claim 1, wherein a first stepping switch constitutes said first device and a second stepping switch constitutes said second device, means for advancing said second stepping switch by one step after each operating cycle of said first stepping switch during which such first switch is successively advanced a plurality of steps, a plurality of utilizing circuits connected with said generator, a plurality of control contact means respectively associated with said utilizing circuits, supervising switching means cooperating with said last named control contact means, and circuit means for said supervising switching means and said control contact means whereby said supervising switching means become operative over one of said control contact means responsive to failure of another such control contact means, and signal means actuated by said supervising switching means responsive to operation thereof.
